(57) CLAIM

The ornamental design for a base member for a sharpening device used to sharpen a cutting tool, as shown and described.

DESCRIPTION

FIG. 1 is a perspective view of the design.

FIG. 2 is a front view of the design of FIG. 1.

FIG. 3 is a back view of the design of FIG. 1.

FIG. 4 is a top plan view of the design of FIG. 1.

FIG. 5 is a right side view of the design of FIG. 1; and,

FIG. 6 is a left side view of the design of FIG. 1.

The dash-dot-dash broken lines in the drawings define boundaries of the claim and form no part thereof. The dash-dot-dash broken lines in the drawings depict portions of the base member that form no part of the claimed design.

1 Claim, 5 Drawing Sheets
